HERMANN SCHELL, OF NUERMBERG, GERMANY.

COOKING APPARATUS WITH STEAM HOOD.

Application filed July 30, 1926, Serial No. 126,000, and in Germany March 16, 1925.

This invention relates to a cooking apparatus with steam hood adapted to be heated by electricity or by gas. The invention has for its object to produce automatically at the correct time the controlling of the source of heat. For this purpose the water from condensation is utilized, according to the invention, which water collects under the steam hood as soon as the temperature for cooking has set in. An alarm signal may be sounded at the controlling of the source of heat.

10 An embodiment of the invention is shown, by way of example, in the accompanying drawing in which:—

Fig. 1 shows in vertical section the cooking apparatus and part of the controlling mechanism.

20 Fig. 2 shows the controlling mechanism for electric heating.

Fig. 3 shows the same mechanism for gas heating.

The cooking apparatus is composed of the heater plate 1 which has projecting angle irons 2, 2, of a trough-shaped metal ring 3 resting upon said angular pieces 2, and of a trough-shaped ring 4 which has an outflow pipe 5. The ring 4 is slightly inclined in order that the water from condensation 30 collected in the same flows towards the outflow pipe 5. On this outflow 5, a finger 6 is fixed which is hollow and perforated and on which, by means of a band 7, a metal ball 8 is suspended. The band consists of a material which dissolves in water, or which 35 loses its solidity if soaked in water, for instance a strip of unsized paper as blotting paper or the like. A water pocket 9 is further arranged on the outflow 5. On a shoulder of ring 4 rests the steam hood 10 which covers the two pans 33, 33 which are placed the one on the other.

The controlling mechanism, Fig. 2, is arranged on an insulated plate 20. A scale beam 12 oscillatably mounted on an axle 11 has at one end a hook 13. The other end of the beam 12 is normally pushed upward by the action of a spring 14. The hook 13 grips then over the interrupting lever 15 oscillatable around a pin 23 and pushed up-

ward by the action of a spring 22. The arm 12 carries a cup 19, which stands underneath the ball 8 and it carries further a locking bolt 16 bearing from behind against the lever 17 of a clockwork bell 18 and locking thus 55 the escapement of the clockwork.

The switch lever 15 comprises an insulated head piece 21. The pivot pin 23 forms one of the contacts the second contact being formed by a terminal 24 in which the switch 60 lever 15 is clamped. Terminals 25, 26 are provided, the latter being electrically connected to the contact 24.

In the form of construction shown in Fig. 3 the gas flows from the gas main through 65 a tubular socket 27 to the casing of the cock 28. A second tubular socket 32 is fixed on said clock casing and designed to conduct the gas to the heating plate 1. On the cock 28 an arm 29 is fixed, a blade spring 70 30 tending to turn this arm upwards. In order to limit the oscillating movement of said arm or lever 29 and to regulate thereby the amount of opening of the gas cock, a stop screw 31 is provided. The other elements of the mechanism are the same as those shown in Fig. 2 and they are designated by the same reference numerals.

The pans 33 project over the rim of plate 1 into the cavity of the metal ring 3, said 80 metal ring 3 intercepting liquid from boiling over, so that this liquid cannot get onto the plate 1. The ring 3 serves further to protect the ring 4 against excessive heating, so that the evaporation of the water from 85 condensation in the ring 4 is prevented. If necessary water might be filled into the cavity of ring 3 so that it evaporates and increases the heating effect. According to whether the operation of the controlling 90 mechanism has to be produced at once or a little later by the collected water from condensation, the water pocket 9 is previously filled entirely or partly with water, or it 95 is left empty. If the water pocket 9 is filled with water, the water from condensation flows at once through the finger 6, destroys the resisting capability of the paper strip 7 and makes the metal ball 8 drop into the cup 19. The scale beam 12 is thus oscillated 100

so that, on the one hand, it releases the locking lever 17 of the alarm bell 18, which begins to sound, and, on the other hand, releases, if electric heating, the switch lever 15, 5 and if gas heating, the cock lever 29, these levers being pushed upward by the action of the springs 22 or 30. At electric heating the current is thus interrupted, and if gas heating the cock is either entirely closed 10 or partly closed, in accordance with the position of the stop screw 31. If the water pocket 9 is empty or only partly filled, this operation is retarded. The electric cooking plate may have several circuits, so that the 15 electric heating can be switched to feeble heating in accordance with the circuits.

As the steam hood 10 rests upon a shoulder of ring 4 it is protected against being dirtied by the water from condensation. It 20 may be less high in accordance with the height of the shoulder.

For gas heating the metal ring 3 is placed upon a gas cooker which is mounted at such height that the outflow pipe has approximately the same distance from cup 19 as at 25 electric heating. The lower pan stands then directly over the gas burner.

The cooking apparatus described presents the further advantage that the rings 3 and 30 4 are only loosely connected with the electric heating plate or with the gas cooker, and that the controlling mechanism is mounted separate from the source of heat, so that all elements can be easily cleaned. 35 The apparatus might be used for baking if the ring 4 and the outflow tube 5 are omitted, and the steam hood is placed directly into the metal ring 3, so that the hot gases flow under the hood and around the material to be baked.

I claim:

1. A cooking apparatus comprising in combination with the cooker proper having a source of heat, a steam hood, a trough shaped ring on which said steam hood rests and designed for collecting the water from condensation, an outflow from said ring, a mechanism for controlling said source of heat, and a means for operating said mechanism by the outflowing water from condensation.

2. A cooking apparatus comprising in combination with the cooker proper having a source of heat, a steam hood, a trough shaped ring on which said steam hood rests and designed for collecting the water from condensation, an outflow from said ring, a mechanism for controlling said source of heat, and a resisting means underneath said outflow said means adapted to lose its resisting capability by the action of the outflowing water from condensation so that it operates said mechanism.

3. A cooking apparatus comprising in combination with the cooker proper having

a source of heat, a steam hood, a trough shaped ring on which said steam hood rests and designed for collecting the water from condensation, an outflow from said ring, a mechanism for controlling said source of heat, a tension means underneath said outflow, and an alarm signal operated thereby when the tension is released.

4. A cooking apparatus comprising in combination with the cooker proper having a source of heat, a steam hood, a trough shaped ring on which said steam hood rests and designed for collecting the water from condensation, an outflow from said ring, a mechanism for controlling said source of heat, a tension means for operating said mechanism by the outflowing water from condensation, and a water pocket in said outflow designed to intercept a portion of the water from condensation to regulate the moment at which said water begins to act upon said means for operating said mechanism.

5. A cooking apparatus, comprising in combination with the cooker proper having a source of heat, a steam hood, a trough shaped ring on which said steam hood rests and designed to collect the water from condensation, an outflow from said ring, a vessel for collecting the outflowing water from condensation, a mechanism for controlling said source of heat, and means for connecting said vessel with said mechanism so that the controlling of the source of heat takes place after a predetermined quantity of water from condensation has passed out.

6. A cooking apparatus comprising in combination with the cooker proper having a source of heat, a steam hood, a trough shaped ring in which said steam hood rests and designed to collect the water from condensation, said ring being inclined in one direction, an outflow tube at the lowest point of said ring, a shoulder in said ring on which said steam hood rests, and a mechanism for controlling said source of heat and operated by the outflowing water from condensation.

7. A cooking apparatus comprising in combination with the cooker proper having a source of heat, a steam hood, a trough shaped ring in which said steam hood rests and designed to collect the water from condensation, said ring being inclined in one direction, an outflow tube at the lowest point of said ring, a shoulder in said ring on which said steam hood rests, a mechanism for controlling said source of heat and operated by the outflowing water from condensation, and a second trough shaped ring underneath said first mentioned ring and designed to protect said first mentioned ring against excessive heating and to carry said steam hood.

8. A cooking apparatus comprising in

combination with the cooker proper having a source of heat, a steam hood, a trough shaped ring in which said steam hood rests and designed to collect the water from condensation, said ring being inclined in one direction, an outflow tube at the lowest point of said ring, a shoulder in said ring

on which said steam hood rests, a mechanism for controlling said source of heat and operated by the outflowing water from condensation.

In testimony whereof I affix my signature.

HERMANN SCHELL.
